METHOD AND APPARATUS FOR SPINNING STAPLE FIBER YARN WITH SIMULTANEOUS DRAFTING

Ludwig Althof, 6 Hohenzollernstrasse,
Dahlerau (Wupper), Germany
Filed June 14, 1961, Ser. No. 117,165
4 Claims. (Cl. 57—51)

This invention relates to a method of spinning a woolen, cotton or other staple fibre yarn in the manner of a carded woollen yarn, with the simultaneous application of draft, from a hard twisted roving, and to apparatus for performing this method.

It is known that fine yarn spinning machines are adapted to convert slivers or rovings into a finished yarn of improved regularity and strength by the insertion of twist through the agency of spindles. The rovings possess no or little twist and are fed to the drafting rollers of the spinning machines in this condition. However, these unconsolidated rovings tend to suffer unwanted drafting which gives rise to variations in the thickness, i.e. in the count of the final yarn.

In systems of spinning without a flyer, hard twisted rovings are used to overcome this drawback. However, these systems have the shortcoming that before entering the drawing frame the rovings are practically completely untwisted. The draft is therefore imparted to substantially untwisted rovings and although this is attenuated it tends to give rise to a "cocky" yarn.

In known systems of spinning coconut and similar fibers their nature necessitates the use of a hard twisted roving. After entering the draw frame the roving is untwisted by imparting false twist to the same so that a section which substantially lacks twist is simultaneously drafted. This method is applicable only to coarse and rough fibers of the nature of coconut fibre. Wool, cotton or other staple fibers do not lend themselves to be spun by this method, because in woollen spinning the completely untwisted loose sliver would break in the drafting.

Further, in known systems of spinning, the spindle is the agent for the insertion of twist as well as the carrier for receiving the yarn. It is disadvantageous that, according to the desired twist of the yarn, the spindle must be rotated at very high speed and the resultant inertial forces limit the size of the package. In known spinning systems the fact that the spindle fulfills two separate functions entails the following drawbacks.

In mule spinning the intermittent operations of spinning and winding make for an uneconomical process. Headstock and carriage require a good deal of floor space and the reversing mechanism is highly complex.

In ring, cap and flyer spinning, continuous operation is achieved by means of the ring with traveller, the cap or the flyer. These auxiliary tools deflect, guide and brake the thread which the spindle rotates, simultaneously causing it to wind itself on to the spindle. The necessary traverse of the auxiliary tools or of the spindle causes the twisting length as well as the tension to vary and this in turn leads to non-uniform twist and to breakages of the thread. The friction between the ring and the traveller or between the thread and the cap, and the inertia of the rotating flyer as well as other factors restrict the speed of the spindle to within limits which are fairly narrow. Supplementary devices which are intended to minimize these defects involve a considerable expenditure in means.

In so-called can spinning frames the insertion of a regularizing draft is impossible. These machines are therefore used only for coarse yarns which are not required to fulfill stringent demands in regard to uniformity and yarn diameter. In order to prevent the thread tension from

2

being transmitted into the can it is known to interpose a twister tube between the spinning can and the draw-off means so that the roving receives only part of the intended twist between the twister tube and the can. However, in 5 this arrangement the spinning process is performed without draft.

All known methods have the defect that with respect to shape and size the packages cannot be wound to meet the requirements of following production stages. The shape 10 and size of the package, which depends upon the nature of the spinning process, is incapable of more than limited modification. It is therefore necessary to interpose a process of re-winding in order to produce the type of package which is suitable for the next operation.

15 It is the object of the present invention to overcome the aforementioned drawbacks and to provide favourable technological conditions for the spinning operation as well as a generally economical procedural technique. Drafting is performed by untwisting the roving in the drafting system to the extent required for slippage between the fibers 20 to be possible, but not more, and two separate tools are used for the insertion of the final twist and for winding the yarn. Spinning is completed without the use of a spindle and the yarn is wound into a package of any desired shape and form to suit the next operation.

The invention provides a method of spinning a woollen, cotton or other staple fibre yarn, in the manner of a carded woollen yarn, with the simultaneous application of draft, by feeding a roving, twisted in the same direction as the 30 finished yarn, into a drafting system for levelling the yarn, which comprises the steps of feeding a hard twisted roving, incapable of yielding to draft and having as many turns as the finished yarn is required to have after allowance is made for the draft, into a drafting system comprising at least one false twister, unwinding said roving in a drafting zone preceding said false twister to the extent required for the roving to yield to draft, submitting the same to draft, and winding the finished yarn which leaves the drafting system into a package.

40 The amount of twist the finished yarn is required to have may be inserted into the roving during its entry into the drafting system.

The hard twisted roving entering the drafting system 45 may be untwisted by a false twister in each of a plurality of consecutive drafting zones until the remaining twist in the zone preceding each false twister permits the roving to yield to the draft applied thereto in each zone, the final yarn leaving the last of the drafting zones being run into a packaging means.

50 The apparatus for carrying out that method comprises a drafting system substantially consisting of a spindle, at least one pair of front rollers, at least one false twister and a pair of drafting rollers, as well as a packaging means substantially constructed in the manner of the packaging means in rewinding frames.

The apparatus for performing the method proposed by the invention will now be described in greater detail by reference to preferred embodiments shown in the accompanying drawings, in which:

FIG. 1 is a perspective view of a spinning apparatus according to the invention for spinning a hard twisted roving;

FIG. 1A is a diagrammatic representation of the amount 65 of twist in the thread in the several working phases in apparatus according to FIG. 1;

FIG. 2 is a perspective view of another embodiment of spinning apparatus according to the invention in which the hard twist is inserted into the roving before entering the drafting system;

FIG. 2A is a diagrammatic representation of the amount

of twist in the thread during the several working phases in apparatus according to FIG. 2;

FIG. 3 is a perspective view of the spinning apparatus of FIG. 2 associated with a double twist spindle;

FIG. 4 is a perspective view of yet another embodiment of the proposed spinning apparatus comprising several drafting fields; and

FIG. 4A is a diagrammatic representation of the amount of twist in the thread during the several working phases in apparatus according to FIG. 4.

The illustrated apparatus is intended for spinning wool, cotton or other staple fibre yarn, in the manner of a carded woollen yarn, comprising the application of draft. In a conventional manner an initial roving 1 has been hard twisted in a roving frame and becomes available in the form of a package on a spindle 2. Twist can also be imparted to the roving 1 by rotating the spindle 2.

From the spindle 2 (FIG. 1) the roving 1 enters the drafting system. This contains a rotary false twister 3 into which the roving enters through an inlet 4 and which it leaves through an outlet 5. The false twister 3 is disposed between a pair of front rollers 6 and a pair of drafting rollers 7 and may be fixed or slidably displaceable by means of an adjustable member 16 to permit variation of the length of the drafting field. This rotary false twister 3 may take the form of a twisting tube, twisting rollers, a twisting turbine, or the like. The length of the roving 1 between the pair of front rollers 6 and the inlet 4 of the false twister 3 is gradually untwisted to permit the fibres to slide and at the same time it is drafted by the pair of drafting rollers 7 in a first zone lying between the pair of front rollers 6 and the inlet 4 of the false twister 3. The draft takes effect in this first zone because in a second zone lying between the outlet 5 of the false twister 3 and the pair of drafting rollers 7 the false twister 3 which operates in both directions imparts an additional amount of twist; so that the length of thread in this second zone is a yarn which is incapable of being further drafted. In the first zone, in which attenuation of the roving exclusively occurs, a number of turns is allowed to remain in the roving 1 to retain frictional grip between the fibres. This is calculated to ensure that slippage of the fibres is possible while preventing their separation, that is to say breakage of the thread. After leaving the spinning apparatus consisting of the pair of front rollers 6, the pair of drafting rollers 7 and the false twister 3 the finished spun yarn now having the same amount of twist as before entering the pair of front rollers 6 is wound by packaging means 8 resembling that used in conventional rewinding machines. The packaging means 8 may be suitable for building cheeses, cones or any other kind of package of any shape or size to suit the following production stages. The completed packages may be doffed automatically in any manner known to the art.

In the embodiment shown in FIG. 2 the pair of front rollers 6 is mounted in a revolving frame 9 which is driven. It is to be noted that the revolving frame 9 with the front rollers 6 and the false twister 3 revolve in the same direction. The rollers therefore revolve about their own axes as well as about the axis of the thread. A roving 11 which on the bobbin 10 has no twist will then receive as many turns before it enters the pair of front rollers 6 as will correspond with the difference in speed between the bobbin 10 and the pair of front rollers 6. Overtwisting of the roving 11 is thus avoided if the finished yarn is intended to be a high draft highly twisted yarn.

The insertion of twist into a roving 13 by a double twist spindle 14 which precedes the drafting system, instead of by the roving bobbin, is illustratively shown in FIG. 3. The double twist spindle 14 is of conventional construction and arranged for draw off from the inside of a package 15.

As shown in FIG. 4 the roving 1 may run through a plurality of successive drafting zones lying between the pair of front rollers 6 and a pair of front rollers 6¹, the

pair of front rollers 6¹ and a pair of front rollers 6², and the pair of front rollers 6² and the pair of drafting rollers 7. Each drafting zone is provided with a rotary false twister 3, 3¹, 3² which untwists the thread sufficiently for drafting, such draft being applied in each of said zones, the finished yarn being run on the packaging means 8 after having left the final drafting zone. The distance of the false twisters from the pairs of rollers may be equal or different and, if desired, they may be adjusted when the system is stopped or during operation, by conventional means provided for displacing the pairs of rollers. By mounting all the pairs of rollers 6, 6¹, 6² except the final pair of drafting rollers 7 in frames 9, 9¹, 9² in such a way that they can rotate about their own axes as well as about the axis of the thread in the same direction as the false twisters it is possible to reduce the amount of twist in the zone preceding the pair of front rollers 6 in each second section of the drafting zones lying between the false twister 3 and the pair of front rollers 6¹, the false twister 3¹ and the pair of front rollers 6² etc., excepting the final drafting section lying between the false twister 3² and the pair of drafting rollers 7 to prevent overtwist.

The actual process of spinning will now be described in greater detail by reference to the embodiment shown in FIG. 1: The hard twisted roving 1 on the spindle 2 may have been produced in various ways. The number of turns per unit length of the roving 1 must correspond with the number of turns the fine spun yarn is to possess after allowance is made for the draft. Let it be assumed that the fine spun yarn is to have 350 turns per metre length. Moreover, let it be assumed that the draft is 30%. The roving must therefore have 455 turns per metre

$$\left(= \frac{350.130}{100} \right)$$

The hard twisted roving 1 is drawn off the spindle 2 and taken up by the pair of front rollers 6 to enter the drafting system. The false twister 3 untwists the roving 1 in the first zone between the pair of front rollers 6 and the inlet 4 of the false twister 3 sufficiently to permit the application of draft, but not more. Since during the previous insertion of the hard twist into the roving the finer cross sections have accepted more turns than the thicker sections the latter will yield first to draft when they are untwisted so that drafting causes the varying thicknesses of the thread to be levelled out. The draft applied by the pair of drafting rollers 7 which revolve at higher peripheral speed than the pair of front rollers 6 becomes effective only in the first zone because the drafted yarn in the second zone between the outlet 5 of the false twister 3 and the pair of drafting rollers 7 is retwisted by the false twister in the opposite direction and is therefore incapable of yielding to draft in this latter zone. The number of turns which the spun and drafted finished yarn will now possess depends upon the twist of the roving and the imparted draft. The pair of drafting rollers 7 therefore deliver a yarn to the packaging means 8 from the drafting system which has a twist equalising the twist of the initial roving less the reduction in the twist due to the elongation produced by the draft. The number of turns per unit length which the roving possessed when entering the drafting system is diminished in the first zone and then reinserted in the second zone without any reversal in the directions of rotation. This system provides better facilities of drafting than the hitherto known drafting methods by a rotary tube. The previously inserted hard twist has caused the fibres in the roving to assume a helical shape. The draft elongates these fibre coils in the axial direction, the coil diameters diminishing and giving rise to considerable compressive grip between the fibres during the re-twisting phase in the second zone. The same yarn twists therefore exhibit a higher tearing strength and elasticity than yarns which have been spun by classical techniques. The amount of draft and the length of the first drafting zone are adjusted to the staple length of the fibre. The first drafting

70

zone can be fine-controlled by shifting the false twister 3 when the machine is stopped or during operation. At the end of the spinning process the finished yarn is wound by the packaging means 8, as in a rewinding frame, into packages shaped and constructed as may be desired.

While the method herein described, and the form of apparatus for carrying this method into effect, constitute preferred embodiments of the invention, it is to be understood that the invention is not limited to this precise method and form of apparatus, and that changes may be made in either without departing from the scope of the invention which is defined in the appended claims.

I claim:

1. A method of spinning a woollen, cotton or other staple fibre yarn, in the manner of a carded woollen yarn, with the simultaneous application of draft, by feeding a roving, twisted in the same direction as the finished yarn, into a drafting system for levelling the yarn, comprising the steps of feeding a hard twisted roving, incapable of yielding to draft without breaking of the yarn fibres and having as many turns as the finished yarn is required to have after allowance is made for the draft, into a drafting system comprising at least one false twister, unwinding said roving in a drafting zone preceding said false twister to the extent required for the roving to yield to draft without the breaking of the yarn fibres, submitting the same to draft in such a manner that the roving yields only in the unwound portion preceding the false twister whereby draft occurs only in the zone in front of said false twister, the hard twisted roving entering the drafting system being untwisted by a false twister in each of a plurality of consecutive drafting zones until the remaining twist in the zone preceding each false twister permits the roving to yield to the draft applied thereto in each zone without the breaking of the yarn fibres, the final yarn leaving the last of the drafting zones being run into a packaging means.

2. Apparatus for spinning yarn in the manner of a carded woollen yarn, with the simultaneous application of draft, comprising a drafting system substantially con-

sisting of a spindle, at least one pair of front rollers, at least one false twister having means for simultaneously twisting a roving in opposite directions and a pair of drafting rollers, as well as a packaging means substantially constructed in the manner of the packaging means in rewinding frames, the spindle being embodied in a double twist spindle adapted in conventional manner for draw-off from the inside of a package.

3. Apparatus for spinning yarn in the manner of a carded woollen yarn, with the simultaneous application of draft, comprising a drafting system substantially consisting of a spindle, at least one pair of front rollers, at least one false twister having means for simultaneously twisting a roving in opposite directions and a pair of drafting rollers, as well as a packaging means substantially constructed in the manner of the packaging means in rewinding frames, the spindle being followed by a plurality of consecutive drafting zones each substantially formed by a pair of front rollers and a false twister having means for simultaneously twisting a roving in opposite directions, said drafting zones being followed by the pair of drafting rollers.

4. Apparatus as claimed in claim 3, wherein the spacing of each false twister in relation to the associated pair of rollers is independently adjustable during operation by adjustable displacement of the false twister.
